UNITED STATES PATENT OFFICE

HANS ERICH HOLLMANN, OF DARMSTADT, GERMANY

PRODUCTION OF ELECTRIC WAVES

Application filed June 20, 1929, Serial No. 372,406, and in Germany June 4, 1928.

Application for this invention filed in Germany, June 4, 1928.

My invention refers to the production of electric waves and more especially to means whereby short electric waves can be produced by means of electron oscillation.

As a rule electric oscillations are produced by means of electron tubes in regenerative connection, the circuits of the grid and anode 10 of a three electrode valve being coupled with each other in such manner that oscillation energy is constantly fed back and all losses of energy are covered. Therefore, in a feed back arrangement as above described the 15 smallest oscillations, after having once received an impulse, will rise steadily up to a limit, which is determined merely by the power capacity of the tube. In such a system the frequency of the oscillations is de- 20 termined by an oscillatory system inserted in the circuit, such system being indispensable. The frequency remains absolutely constant throughout the building up of the oscillations to their resonance amplitude.

25 This process is not adapted for the production of very short waves because the time of transit of the electrons within the tube is not negligible any more as compared with the duration of the periods of oscillation. In 30 consequence thereof feed-back conditions, especially as far as they concern the position of the phases of the alternate potential at the grid and the anode, cannot be satisfied any more.

35 Very short waves can be produced according to the method suggested by Barkhausen and Kurz. In this known process the time, during which the electrons remain in the space between the electrodes, determines the 40 frequency, in that a pendulum movement of the electrodes relative to the grid takes place by providing means for a particular field distribution differing essentially from the usual operation of vacuum tube. To this end 45 the grid is imparted a high positive, the anode a low negative potential. The electrons passing through the grid with high velocity are returned by the braking field of the anode and pass again through the 50 grid, whereupon the same phenomenon starts

all over again. Barkhausen and Kurz found that the wave length depends merely upon the electric field intermediate the electrodes and that an oscillatory system connected with the tube does not influence the frequency but merely increases the oscillation energy.

55 I have now found that if an oscillatory system coupled with the tube is suitably tuned, the frequency will jump suddenly as the wave length of the pendulum motion of the electrons merges into the natural wave length of the tuning system.

60 In the drawings affixed to this specification and forming part thereof, a diagram illustrating this invention is shown by way of example.

65 In this diagram R represents the tube, having an anode F, a grid G, and a cathode H. The grid and anode are connected with two parallel wires L and L', respectively, and B is a bridging condenser which is displaceable along these wires.

70 To different positions of the condenser B correspond the wave lengths shown by the curve. The jump, by which the Barkhausen-Kurz frequency merges into the natural wave length of the parallel wire system, is made visible at A. These jumps of frequency are probably caused by the circumstance that the electrons swinging between the electrodes excite the outer oscillation system, so that the alternating potentials of the oscillating system are superimposed upon the direct current potentials of the tube electrodes. These alternating potentials now react on the exciting electron oscillations in a manner to increase their frequency. The wave length of the electron oscillations, if any alternating potential E_o is superimposed upon the direct current potential E_g of the grid electrode, is determined by the theoretical formula:

$$\lambda = \frac{4000 \sqrt{E_g - E_o} d}{E_g - \frac{4 \cdot E_o}{\pi^2}} \quad 85$$

90 wherein d represents the distance between the electrodes.

95 The formula shows that λ is gradually 100

shortened in proportion to the increase of E_o as can be guessed from the following numerical example:

If $E_g = 500$ volt and $d = 0.5$ cm., E_o and λ are found to have the following values:

E_o	0	100	200	300	400	Volt
	89,5	86,9	82,5	74,6	58,8	cm.

Now if the natural wave length of the tuning system is less than the wave length of Barkhausen-Kurz the exciting electron frequency, in consequence of the alternating potentials added to the direct current potentials of the electrode, will approach the resonance wave length of the wire system. This results in an increase of the alternating potentials, whereby the exciting wave length is further shortened and approaches further the resonance wave length. Obviously in this manner a frequency rise is obtained whereby the frequency will increase until it attains the natural frequency of the oscillatory wire circuit. A proper increase of the exciting frequency beyond resonance would result in a weakening of the alternating field and consequently a decrease of the oscillations.

The present invention is thus based on the fact that the electrons swinging between the electrodes are received from the alternating fields, which they themselves have induced, an increase of frequency, whereby a gradual frequency rise is brought about. This phenomenon may be compared to the phenomena occurring in feed-back systems in which, however, merely an energy rise at constant frequency takes place. In the present case, too, where ultra-short waves are produced, an increase of energy is obtained also besides the frequency rise as described.

Various changes may be made in the details disclosed in the foregoing specification without departing from the invention or sacrificing the advantages thereof.

In the claims affixed to this specification no selection of any particular modification of the invention is intended to the exclusion of other modifications thereof and the right to subsequently make claim to any modification not covered by these claims is expressly reserved.

I claim:

1. In a system for producing ultra high frequency electric oscillations by electron pendulum movements within a vacuum space in a retarding field arrangement including an oscillatory system for utilizing said oscillations, the method of increasing the natural electron oscillating frequency determined by the field strength which consists in tuning said system to a frequency greater than said natural frequency of said electron movements.

2. In a system for producing ultra high frequency electric oscillations by electron

pendulum movements about the grid electrode of a vacuum tube having a high positive potential applied and a wire tuning system connected to said grid electrode, the method of increasing the natural frequency of the electronic oscillations determined by said potential which consists in tuning said wire system to a frequency greater than said natural frequency.

In testimony whereof I affix my signature. 75
